UNITED STATES PATENT OFFICE.

JOSEPH KISH, OF COBALT, ONTARIO, CANADA.

FIRE-ESCAPE.

1,156,908.

Specification of Letters Patent.

Patented Oct. 19, 1915.

Application filed August 16, 1915. Serial No. 45,843.

To all whom it may concern:

Be it known that I, JOSEPH KISH, a subject of the King of Hungary, residing at Cobalt, in the Province of Ontario, Canada, 5 have invented certain new and useful Improvements in Fire-Escapes, of which the following is a specification.

This invention relates to certain new and useful improvements in fire escapes.

10 An object of the present invention is to provide a fire escape that may be easily and quickly positioned in engagement with the lower sill of an open window while a manually-controlled carriage or car is adapted 15 to be moved to position adjacent the window for the reception of persons within a burning building and to be lowered at will of the operator.

20 A further object of the invention is to provide a portable fire escape that is adapted to be positioned at an open window of a building and retained in position by hook members engaging the lower window sill while that portion of the device positioned 25 exteriorly of the building includes hinged arms that support the vertically shiftable passenger cage or car which forces the support for the hinged arms into positive engagement with the front wall of the building. 30

With these general objects in view and others that will appear as the nature of the invention is better understood, the same consists in the novel construction, combination 35 and arrangement of parts hereinafter more fully described, illustrated in the accompanying drawings, and then claimed.

In the drawings forming a part of this application and in which like designating 40 characters refer to corresponding parts throughout the several views:—Figure 1 is an end elevational view of a portion of a building, partly shown in section, with the present fire escape in operative position thereon, and. Fig. 2 is a detail perspective view of the fire escape mechanism.

Referring more in detail to the accompanying drawings, the reference numeral 10 designates in general a building or other 50 structure including the front wall 11 and the usual window openings 12 while the reference numeral 13 designates the lower sill of each window.

55 The device comprises more specifically, a pair of hooked members 14 that are adapted to be mounted on the window sills 13 as

indicated in Fig. 1 while enlargements or heads 15 are carried by the inner ends of the hooks 14 which will prevent the accidental displacement of the device from the window sill by the engagement of the said heads with the inner edge of the window sill as is possible from an inspection of Fig. 1. The hook arms 14 extend outwardly of the window openings 12 and downwardly as at 60 16 to be hingedly connected at their lower ends to outstanding ears or lugs 17 carried by the outer face of the wall-engaging plate 18. The wall-engaging plate 18 is further provided with pairs of coöperating spaced 70 lugs or ears 19 positioned inwardly of the lugs 17 and to which is hingedly connected at their rear ends the arms 20 carrying depending portions 21 at the outer ends thereof and bifurcated to provide lug extensions 75 in which are journaled as at 22, sheave pulleys 23.

The passenger cage or car is supported by the sheaves 23 and includes the car bottom 24 carrying spaced pickets 25 connected at 80 their upper ends to the reinforcing band 26. The corner posts or pickets of the car carry eyelets 27 to which are connected the cable members 28 joined at their ends to an eye 29 and continuing in a single supporting 85 cable 30 that passes over the sheave pulley 23 and extends to the ground as is indicated in Fig. 1 in position, and under control of the operator.

The ladder section is associated with the arms 20 and extends from a point within the room to a point without the room and terminates in a position so that persons climbing over the ladder may be in position 90 to step into the car 24. This ladder includes 95 a pair of side rails 31 having curved inner ends 32 to provide hooks for engaging the window-sill 13 while the side rails 31 have a pivotal connection with the outer ends of 100 the arms 20 at the angle bend thereof, the ladder rung 33 extending laterally of the side rails as at 34 and passing through the said arms 20 and retained in its position by suitable fastening means such as cotter pins. The relative angular position between the side rails 31 and the arms 20 is controlled 105 by the links 35 that are connected at their upper ends as at 36 to the projecting end of a rung 33 while the lower ends of the links 35 have a pivotal connection 37 in the reduced portions provided in the inner face 110 of the arms 20. By this construction, the

ladder is held in substantially rigid condition with respect to the arms while a swinging extension 38 is hinged to the outer ends of the side rails 31 and is in a position to 5 hang directly above the car 24 when the said car is elevated as is indicated.

In the use of the device, the hook arms 14 are positioned over a window sill 13 as indicated in Fig. 1 while the wall plate 18 is 10 adapted to engage the wall 11 of the building. The weight of the car 24 supported on the arms 20 will be sufficient to force the wall plate into positive engagement with the wall while the device is further forced into 15 such position by the weight of a person on the outer end of the ladder while the inner ends of the ladder are hooked as at 32 to engage the window sill. Persons desiring to make an exit from the building climb over 20 the ladder and step therefrom into the car 24 while the attendants for the apparatus control the rising and lowering movement of the car.

While the form of the invention herein 25 shown and described is what is believed to be the preferred embodiment thereof, it is nevertheless to be understood that various forms, modifications and arrangements of the parts may be made without departing 30 from the spirit and scope of the invention as claimed.

What I claim as new is:

1. A fire escape including a wall plate, a pair of hook members hingedly connected

to the ends of the plate, a pair of outstanding arms hingedly connected to said plate inwardly of the hook arm connection, downwardly-projecting extensions carried by said arms, sheave pulleys mounted in said extensions, a ladder including a section fixed 35 to said arms, a swinging ladder section carried by the fixed section, a cable passing over said sheave pulleys, and a passenger car supported by said cable.

2. A fire escape including a wall plate, 40 hook arms carried thereby, outstanding arms pivoted to said wall plate, a ladder section fixed to said arms, hooks carried by the inner end of said ladder, and a car supported on said arms adapted for vertical 45 movement.

3. A fire escape including a wall plate, hook arms carried thereby, a ladder associated with said plate, means carried by said plate for supporting the ladder, and a cable-supported car associated with said means. 50

4. A fire escape comprising in combination with a plate provided with hook arms and outstanding arms, a ladder fixed to said arms, hooks carried by the inner ends of the ladder side rails, and a cable-supported car associated with said arms. 55

In testimony whereof I affix my signature.

JOSEPH KISH.
